(57) **CLAIM**

We claim the ornamental design for a model vehicle pivoting axle carrier holder, as shown and described.

DESCRIPTION

FIG. 1 is an upper, right, front perspective view, to include the mirror image, of a model vehicle pivoting axle carrier holder showing our new design;

FIG. 2 is a left side elevation view thereof;

FIG. 3 is a right side elevation view thereof;

FIG. 4 is a rear elevation view thereof;

FIG. 5 is a front side elevation view thereof;

FIG. 6 is an upper plan view thereof;

FIG. 7 is a lower plan view thereof;

FIG. 8 is a lower, left, rear perspective view thereof; and, FIG. 9 is a lower, right, rear perspective view of the model vehicle pivoting axle carrier holder.

In the drawings, the broken lines illustrate portions of the model vehicle pivoting axle carrier holder that form no part of the claimed design.
